UNITED STATES PATENT OFFICE.

DAVID GEESNER, OF WORCESTER, MASSACHUSETTS.

CLOTH-WINDING MACHINE.

1,139,513.

Specification of Letters Patent.

Patented May 18, 1915.

Application filed February 7, 1910. Serial No. 542,386.

To all whom it may concern:

Be it known that I, DAVID GEESNER, a citizen of the United States, residing at Worcester, in the county of Worcester and 5 State of Massachusetts, have invented certain new and useful Improvements in Cloth-Winding Machines, of which the following is a specification.

My invention relates to new and useful 10 improvements in cloth winding machines, and is an improvement on that machine forming the subject-matter of my pending application for United States Letters Patent, filed August 4, 1908, and serially numbered 446,958, which eventuated in Letters 15 Patent No. 994,075, dated May 30, 1911.

The present invention contemplates, first, 20 means for positively driving the spreader bar disclosed in said application, and, second, means for adjusting or regulating the travel of the cloth sidewise toward the receiving roll so that the cloth will always travel in a straight path, and be rolled list upon list whereby a substantially perfect cylindrical roll is produced. This adjusting is 25 manually controllable by a single operator, which is of great advantage over the former construction, as, in the latter, two men, one on each side of the machine, were necessary 30 to guide the cloth in its travel to the receiving roll, and, third, means whereby the cloth and apron may be conveniently and expeditiously stripped from the steaming roll.

35 The invention consists in the improved construction to be fully described herein-after and the novelty of which will be particularly pointed out and distinctly claimed.

I have fully and clearly illustrated my 40 invention in the accompanying drawings to be taken as part of this specification and wherein—

Figure 1 is a view in side elevation of the improved machine showing the driving 45 means for the spreader bar and the means for controlling the travel of the cloth to the receiving roll. Fig. 2 is a view in side elevation of the improved machine showing the means for stripping the cloth from the

steaming or other roll. Fig. 3 is a top plan 50 view of the machine. Fig. 4 is an end elevation looking toward the right of Figs. 1 and 2. Fig. 5 is a view in end elevation of the machine showing a modified roll shifting means for regulating the path of 55 travel of the cloth or apron through the machine. Fig. 6 is a view in side elevation of the construction shown in Fig. 5. Fig. 7 is a section on the line A—B of Fig. 6. Fig. 8 is a detail view of the scored 60 spreader bar detached from the machine.

Before describing the improvements embodying my present invention, I will describe briefly the construction forming the subject-matter of my application Serial No. 65 446,958.

E designates as a whole the frame of the machine, the same comprising base or feet members 1, 1 connected by the ties 2, 2, the vertical curved standards 3 diverging outward near their upper ends to form a proper support for the carriages and rolls, and 4, 5 indicate ties or girts connecting the standards at their upper end portions.

11 designates the cloth-receiving roll 75 mounted in bearings on the frame and 18 is the main reciprocating carriage upon which is mounted the presser roll 23 which engages the cloth-receiving roll, said carriage being driven in one direction by a 80 pinion 25 on the frame meshing with racks 26 on the carriage. On the carriage 18 is a supplemental carriage 19 reciprocable on the carriage 18, and in which is journaled a stretcher roll 20, said carriage 19 being 85 movable by means of a shaft 27 mounted in brackets 29 in the carriage 18, said shaft carrying shackle cams 30 to which are linked one end of connecting arms 31, the opposite end being connected at 32 to the supplemental carriage. The construction of the supplemental carriage just described permits the stretcher roll 20 mounted thereon to be moved back from the roll 23 so as to create an opening between said roll 23 and 95 the stretcher roll 20 to enable an operator to conveniently thread the cloth between said rolls, this movement being accomplished.

2
by manually rotating the shaft 27 in a direction away from the stretcher roll 20; that is, counter-clock-wise, as shown in Fig. 1, a reverse movement of said shaft operating to move the carriage 19 toward the roll 23. As the particular means for operating this shaft 27 does not form the subject-matter of this application and is not claimed herein, I have not deemed it necessary to illustrate the same. Also rotatably mounted in the carriage 19 are brackets 21, supporting friction bars 37, 38, 39 with which coöperate friction bars 40, 41 mounted on a hinged frame 22, by means of which the sets of bars are adjusted relative to each other to regulate the degree of friction on the cloth.

The apron roll is shown at 14, and the cloth roll at 15, the bearings for said rolls being shown at 16, 16 and 17, 17, respectively, mounted on the frame. The bearings 16 are slidably mounted on the frame and are operable by means of screws 120 into the socket bearing 17, or to withdraw

25 the roll therefrom.
to move said bearings to push the roll shaft
The prime mover, consisting of a driving shaft 47, from which the various elements of the machine are driven is shown supported in suitable bearings on the under side of the cross bar of frame E connecting the legs or standards 1-1 of the machine frame. The particular arrangement of gearing for driving this shaft is not shown, as it forms
35 no part of my present invention.

42 designates a spreader roll the surface of which is scored in order to spread the apron from the center thereof toward the edges as said apron contacts with this roll
40 in order that all wrinkles or creases will be removed from the apron before it is rolled with the cloth on the roll 11. This spreader roll is preferably supported in brackets 43 depending from the under side of the carriage 18, the arrangement being such that when the carriage and the rolls carried thereby are moved back and forth toward the roll 11 the spreader roll 42 will be bodily moved with the carriage. As heretofore stated, the present invention in one of its aspects contemplates means for positively driving the spreader roll 42 from the prime mover 47 at all times during the reciprocation of the carriage 18 irrespective of the
55 change of position of the spreader roll. This driving means is preferably constructed as follows: Mounted on the prime mover is a pulley *a* about which passes an endless belt *b* which in turn drives a pulley *c* loosely running on a stud *c'* on a swinging arm or lever *d*, pivotally connected to the frame of the machine as at *d'*. Arranged coaxially with the pulley *c* and fast thereto is a second pulley *c''* adapted to turn there-
60 with, and which is connected by an endless
65

belt *e* with a pulley *e'* mounted on the shaft of the spreader roll 42. By this arrangement it will be seen that rotary motion will be transmitted from the prime mover 47 to the spreader roll 42, and associated with these driving belts, just described, I provide means whereby they will always be maintained taut to properly drive the spreader roll 42 irrespective of changes of position of said roll relative to the prime mover. In order to accomplish this result, I mount upon the frame E a swinging element in the form of a weighted lever *f* in the free end of which is journaled a grooved pulley *f'* which presses upon the belt *b* serving to maintain the same taut. The lever *f* may be provided with suitable weights *f''*. The swinging element or lever *d* may also be provided with a weight *d''* to increase the gravitation thereof and insure the belt *e* being maintained taut. It will be apparent that as the carriage 18 reciprocates back and forth relative to the roll 11 the positions of the belts will be changed so that they are either slackened or the tension thereof increases according to the position taken by the spreader roll 42. If, for instance, the carriage and spreader roll are in the position shown in Fig. 1 and the carriage is retracted from the roll 11 the tension of the belt *e* will be decreased as the carriage moves toward the position shown in Fig. 2, the slack in the belt being taken up by the gravitation of the weighted swing lever *d*. It will be seen that this gravitation of the element *d* will cause the belt *b* to be slackened, but this will be compensated for by the action of the weighted pulley *f'* on the lever *f*. The slackening of the belt *e* takes place until the axis of the spreader roll 42 is substantially above the axis of the pulley *c* and the continued movement of the spreader roll away from the roll 11 will take up some of the slack in the belt *e* until the spreader roll reaches the position shown in Fig. 2, when the belt *e* will engage with a belt tightener pulley *g* mounted at the curved part 3 of the frame E, said pulley helping to maintain the proper tension on the belt *e*. When the spreader roll is in the position shown in Fig. 2, the lever *d* will be raised, as shown in Fig. 2, increasing the tension on the belt *b*. It will be seen that by this arrangement of belt-drive novel and efficient means is provided for driving the spreader roll without regard to the position the same takes relative to the prime mover 47. The driving connections between the spreader roll 42 and the prime mover 47 are preferably so constructed and proportioned as to drive said roll at a greater velocity than the surface speed of the apron which results in the apron being spread no matter in which direction it travels.

I will now proceed to describe the means

whereby the cloth delivery roll can be shifted sidewise or adjusted so as to insure a straight travel of the cloth through the machine to the roll 11.

- 5 Mounted upon one end of the frame are brackets h upon the free end of which are arranged guide ways h' , into which are dovetailed and arranged in longitudinal alignment with each other the bearing blocks h^2 , said bearing blocks carrying the end bearings for the cloth roll h^4 . By this arrangement the bearing blocks h^2 with the roll h^4 resting therein may be shifted transversely of the machine so that the cloth 10 may be laterally moved to guide it in its forward travel. Suitable means may be provided for manually shifting the bearings of the delivery roll but I prefer to employ that means which will now be described.
- 15 Pivotedly mounted on each of the brackets h is a double sector i , said sectors having opposite sets of gear teeth i' , the sets of gear teeth on one side of the pivot and the sectors meshing with racks i^2 rigidly connected to the bearing blocks h^2 . The opposite sets of gear teeth on the sectors from those engaging with the bearing blocks h^2 for the roll h^4 engage with racks i^3 mounted on a reciprocating element i^4 extending transversely of the machine and mounted in suitable guides i^5 thereon. Extending from one side of the frame is a bracket j in the free end of which is fulcrumed intermediate its ends a hand-lever j' , one end of said lever being connected to the member i^4 by means of a link j^2 . It will be seen that by moving the hand-lever j' in the positions indicated in dotted lines in Fig. 3 that the element i^4 will rock the double segments on their pivots and impart a reciprocatory movement to the cloth roll bearings. It will be noted that the arrangement of means for shifting these bearings is such that the bearings move in the same direction taken by the hand-lever when operated; that is, if the hand-lever is moved to the left, the bearings will be correspondingly moved, and the same is true when the hand-lever is moved to the right.
- 20 In Figs. 5, 6 and 7 I have shown a modified form of my invention in so far as relates to the means for adjusting the cloth roll to regulate the travel of the cloth to the roll 11. In this form of the invention the cloth roll 15 is mounted upon a square shaft k and is adapted to slide longitudinally thereof, said shaft being mounted in and adapted to turn with stud-bearing shafts 16-17, heretofore described, said shafts being rotatably mounted in bearings in the main frame.
- 25 Mounted on the base of the frame, preferably upon the cross tie 2, are a pair of brackets k' in which is slidably mounted a reciprocating member k^2 the ends of which are provided with arms k^3 which project in proximity to the respective ends of the roll
- 30 and are adapted to engage the same to shift the roll whenever the element k^2 is reciprocated. The means for operating the element k^2 preferably consists of a hand-lever l fulcrumed at l' on the main frame and connected to the element k^2 by a link l^2 , said lever having a locking device l^3 cooperating with a segment l^4 by means of which the lever may be locked in a central position when so desired. It will be seen that by shifting the hand-lever to one side from the other from its central position a corresponding movement will be given to the element k^2 and that the latter, through the agency of the arms k^3 will impart a corresponding movement to the cloth roll mounted on the shaft k . In Figs. 6 and 7 I have shown this form of the invention applied to the apron roll 14 and the cloth roll 15, but, as the construction is the same in both instances, a description 35 of one is deemed sufficient for both.
- 40 I will now describe the means for unwinding the cloth and apron from the roll 11 after the same has been taken from the steaming apparatus, or when, for any other reason, it is desired to remove the cloth and apron from said roll. This means comprises two supporting members m preferably of wood, although not necessarily so, the ends of said members being provided with metallic forks m' which are adapted to set over supporting pins m^2 mounted on brackets m^3 secured to the tie 4 of the main frame (on the opposite side to that which carries the reciprocating carriage 18.). When adjusted for performing the unwinding operation, the forked ends of the said members are set over the pins m^2 mounted on said brackets, the opposite ends of members extending up and over the cloth containing roll 11, and in 45 the upper forked ends of said members m is rotatably mounted a lap roll m^4 which is adapted to receive the cloth from the roll 11. This arrangement is such that during the unwinding operation the roll m^4 rests in surface contact with the cloth on the roll 11, this position being maintained by force of gravity. When the unwinding operation is to take place, the apron is passed over the pressure roll 23, by the spreader roll 42, and thence down to a take-up roll mounted on the frame of the machine; for instance, the roll 14, as shown in Fig. 2, and the cloth to be removed from the roll 11 is wound on or secured to the lap roll m^4 . The roll 14 is then revolved to take up the apron and this operation of unwinding the apron from the roll 11 revolves the latter which, through its frictional contact with the lap roll m^4 , revolves said roll m^4 in the proper direction to peel off and unwind the cloth from the roll 11, so that both the apron and cloth are stripped from the roll 11, the apron being wound upon the roll 14 and the cloth being rolled upon the lap roller m^4 .

It will be noted from the above description, taken in connection with the drawings, that the entire unrolling of the cloth and the re-rolling of the same upon the roller m^4 is accomplished by the pull on the apron exerted thereon from the driven roll 14.

It is thought that the operation of the several features of the invention described will be clearly understood from the above 10 description taken in connection with the drawings, but said operation, for the sake of clearness, may be stated as follows: Referring particularly to Figs. 1, 2, 3 and 4, when the winding operation is to take place, 15 a roll h^4 carrying the cloth to be wound is mounted upon the sliding bearing-blocks h^3 and another roll carrying the winding apron is mounted in the bearings on the base of the frame; for instance, the roll 14, the 20 apron being carried up through the frame in contact with the spreader roll 42, and thence between the cloth stretcher 20 and presser roll 23, over the presser roll 23, and wound onto the receiving roll 11. The cloth, 25 to be wound, is then passed through the friction device and may pass under the stretcher roll 20 and thence over the presser roll 23 onto the receiving roll 11, and the latter, being positively driven, the apron and cloth 30 are wound up together on said roll 11. As fully set forth in my prior application, as the receiving roll increases in size, due to the cloth and apron wound thereon, the carriage carrying the stretcher roll, presser roll 35 and spreader moves back away from the receiving roll as the latter increases in size. During this operation the spreader roll 42 is driven positively to remove the wrinkles from the apron, the said roll being so scored 40 as to smooth the apron outwardly from the central portion thereof. As the carriage 18 moves back it will be seen that the belt e will at first be slackened, but this will be compensated for by the gravitation of the lever d , 45 and the corresponding slackening of the belt b will be taken up by the weighted belt pulley f' . This operation takes place, as heretofore stated, until the spreader 42 is over the pulley c when the continued motion of said spreader toward the position 50 shown in Fig. 2 brings the belt e in engagement with the immovable belt tightener g to help maintain the tension on the said belt. During the winding a single operator 55 standing adjacent the delivery roll can conveniently, by shifting the lever j' , move the delivery roll from side to side so that the cloth in passing through the machine is so adjusted that selvage will always run on 60 selvage on the winding roll 11. It will be seen that when the unwinding operation is taking place the apron runs over the presser roll 23 and thence down in contact with the spreader 42 to the roll 14 upon which it is 65 wound. During this operation the direc-

tion of revolution of the spreader 42 is not reversed but continues in the same direction as when the winding operation is in progress, but owing to the construction of the driving means for the spreader the latter is driven at a greater velocity than the surface speed of the apron in contact therewith so that said spreader operates to spread the apron no matter in which direction the apron is traveling.

70

While I have shown and described the invention as being applicable for driving a spreader bar or roll, I desire it understood that I do not desire to limit myself to a construction which is specific to spreader 80 bar or roll as, in its broad aspect, the invention is applicable to any revoluble cloth treating means which changes its position relative to its driving means during the cloth treating operation.

85

What I claim and desire to secure by Letters Patent of the United States is:—

1. In a cloth-winding machine, a web-delivery roll, a web-receiving roll, a spreader roll between the said delivery-roll and receiving-roll and spaced away from the receiving-roll and engaging the web passing between said first-named rolls, means whereby the spreader roll is movable toward and away from the said receiving-roll, and power means for positively and continuously driving said spreader roll during its said movement and while engaging the web.

90

2. In combination, a cloth-receiving roll, a spreader roll out of contact with the receiving-roll, a support for the spreader roll whereby the spreader roll is moved away from the receiving roll as the latter increases in size, and means for positively driving the spreader roll irrespective of its 105 position relative to the receiving roll.

100

3. In a cloth-winding machine, in combination, a web-receiving roll, a web-delivery roll, a spreader roll scored to spread the web between said first-mentioned rolls when the 110 web travels in one direction, means whereby the direction of travel of the web may be reversed, and means for continuously driving said spreader roll in one direction at a greater surface velocity than the rate of 115 travel of the web, irrespective of the direction of travel of the web.

110

4. In combination, a cloth roll, a spreader roll over which an apron passes to the cloth roll, means whereby the spreader roll is 120 movable toward and away from the cloth roll, and means for continuously revolving the spreader roll during its movement relative to the cloth roll.

120

5. In combination, a cloth-receiving roll, a 125 spreader roll movable toward and away from the cloth-receiving roll, means for continuously driving said roll during its movement comprising a prime mover, a belt gearing connecting the prime mover and the spreader 130

130

- roll to drive the latter, and means for maintaining the belt gearing effective irrespective of the position of the spreader roll relative to the cloth roll.
5. 6. In combination, a cloth roll, a spreader roll movable toward and away from the cloth roll, a prime mover, a swinging element, a driving belt connecting the prime mover and the swinging element and a second driving belt connecting said swinging element and the spreader roll.
10. 7. In combination, a cloth roll, a spreader roll movable toward and away from the cloth roll, a prime mover, a swinging element, a driving belt connecting the prime mover and the swinging element, a second driving belt connecting said swinging element and the spreader roll, and a belt tightener acting on the first-named belt.
15. 8. In combination, a cloth-receiving roll, a spreader roll movable toward and away from the cloth-receiving roll, a prime mover, a vertically swinging lever fulcrumed on the frame, a pair of belt pulleys on said lever, a driving belt connecting the prime mover and one of said pulleys, and a second driving belt connecting the other pulley with the spreader roll.
20. 9. In combination, a cloth-receiving roll, a spreader roll movable toward and away from the cloth-receiving roll, a prime mover, a vertically swinging lever fulcrumed on the frame, a pair of belt pulleys on said lever, a driving belt connecting the prime mover and one of said pulleys and a second driving belt connecting the other pulley with the spreader roll, a gravitating belt tightener acting on the first-named belt, and a fixed pulley on the frame to be engaged by the second belt.
25. 10. In combination, a cloth-receiving roll, a spreader roll movable toward and away from the cloth-receiving roll, and means for driving said roll during such movement comprising a gravitating element, a driving pulley thereon, a belt connecting the driving pulley with the spreader roll, and means for driving the driving pulley.
30. 11. In combination, a frame, a cloth-receiving roll, a spreader roll movable toward and away from the cloth-receiving roll, a gravitating element, a pulley on said element, a driving belt connecting the pulley and the spreader roll, a fixed pulley on the frame adapted to engage the belt to maintain the same taut when the spreader roll is in one position relative to the receiving roll, and means for driving the pulley on the gravitating element.
35. 12. In combination, a cloth-receiving roll, a delivery mechanism movable toward and away from the receiving-roll, said delivery mechanism including a presser-roll adapted to engage the cloth-receiving roll, a spreader-roll supported beneath the presser-roll, and means for continuously driving said spreader-roll during the movement of the delivery mechanism.
40. 13. In combination, a cloth roll, slideable bearings for the ends of the roll, racks on the bearings, segmental racks engaging said first-named racks, and manually-operated means connecting the racks for rocking the segmental racks to simultaneously slide the bearings whereby to move the roll longitudinally.
45. 14. In combination, a cloth and apron-containing roll, an apron-receiving roll, a cloth-receiving roll resting in surface contact with the cloth-containing roll and adapted to have the cloth wound thereon, and means for drying the apron-receiving roll whereby the apron is wound thereon to revolve the cloth-containing roll and cause the cloth to be wound on the cloth receiving roll.
50. 15. In combination, a cloth-containing roll, a cloth-receiving roll arranged in surface contact with the cloth-containing roll, a removable support for the cloth-receiving roll, and means for driving the cloth-containing roll whereby the receiving roll is driven to have the cloth wound thereon.
55. 16. In a winding machine, in combination, a frame, brackets thereon, a cloth-containing roll on the frame, and a winding attachment comprising removable supports engaging the brackets, a cloth-receiving roll mounted in the supports and arranged in surface contact with the cloth-containing roll, and means for driving the cloth-containing roll whereby the cloth-receiving roll is revolved to have the cloth wound thereon.
60. 17. In a cloth-winding machine, a web supply-roll, a web receiving-roll adapted to have the web wound thereon in roll form, a revoluble web spreading-roll between said supply-roll and said receiving-roll and movable toward and away from the receiving-roll and arranged to continuously engage the web during said movement between said rolls and before the web reaches the receiving-roll, and means for continuously driving said spreader-roll during its movement toward and away from the web receiving-roll.
65. 18. In combination, a cloth-receiving-roll, and a cloth-delivery-mechanism comprising a carriage movable toward and away from the receiving-roll, a presser-roll and a spreader-roll on the carriage movable therewith, said spreader-roll being spaced from the receiving-roll, and means for continuously driving the spreader-roll during its back and forth movement relative to the receiving-roll.
70. 19. In combination, a roll adapted to have a web wound thereon and unwound therefrom, a spreader roll adjacent the said roll, said spreader-roll being spaced to spread the web.

web as it passes to said roll, and means for driving said spreader-roll at greater surface velocity than the movement of the web whereby the web is spread irrespective of whether it passes to or from the said roll.

In testimony whereof I have hereunto

signed my name in the presence of two subscribing witnesses.

DAVID GEESNER.

Witnesses:

M. E. McNINCH,
C. G. HEYLMUR.

It is hereby certified that in Letters Patent No. 1,139,513, granted May 18, 1915, upon the application of David Gessner, of Worcester, Massachusetts, for an improvement in "Cloth Winding Machines," errors appear in the printed specification requiring correction as follows: Page 2, line 21, before the word "mounted" insert the word *rotatably*; same page, after line 23, insert the words *to move said bearings to push the roll shaft*; same page, strike out line 26; and that the said Letters Patent should be read with these corrections therein that the same may conform to the record of the case in the Patent Office.

Signed and sealed this 15th day of June, A. D., 1915.

[SEAL.]

J. T. NEWTON,

Acting Commissioner of Patents.
